*S. Willard,
Cutting Veneers.
Patented May 9, 1832.*

May 9, 1850

Simon Willard of Cincinnati Ohio
Letters Patent

The Schedule referred to in these Letters Patent and making part of the same containing a description in the words of the said Simon Willard himself of his improvement in the Board Shearing machine.

To all whom these presents shall come. Be it known that I Simon Willard of the City of Cincinnati in the County of Hamilton and State of Ohio, have invented a new and useful improvement, which consists in the application of the combination of a pair of horizontal shears, with a vibrating cutter and the requisite machinery as herein after set forth, and applied by me to the new and useful purpose of cutting boards, planks, or slabs lengthwise, into plastering laths, or narrow flooring and other joiner work, and strips of various lengths and breadths, as may be required for various other uses, in a manner never in useful operation before. this application as in the following Specification the same is set forth and constitutes a new and useful Board Shearing machine.

This Board shearing machine when constructed upon a scale only sufficiently large to cut plasterer's laths four feet in length, one inch wide, and a fourth thick, with the vibrating cutter calculated to vibrate in a vertical manner consists of a supporting ^{frame} and a driving shaft, one or two balance wheels and a pair of horizontal shears, and other requisite parts, as herein after distinctly explained viz. The supporting frame is composed of a pair of sills, about twelve feet in length, five inches thick, and ten or fifteen inches wide, framed together on the lower ends of a pair of upright posts of about the same length and size, and these in supported by a pair of long braces of the same thickness, framed together into the sills and posts. The sills of the two

Drawing

horizontal and frames are joined four and a half feet apart to the ends of one or two cross sills. A horizontal fixed cutter beam of the same length of the cross sills, about a foot thick is framed into the upright posts with its upper edge about three feet high. On the frame is the post as may be required to support the operation of the machinery, according to the position the driving shaft is placed, in relation to the shear.

The long machine is required to cut boards sixteen feet in length a cap beam may be framed within the upper ends of the upright post sufficiently large to support the driving shaft when more than one pair of pilers, is required to strengthen the vibrating cutter beam against springing in cutting flooring or other long strips. By means of boxes within which the driving shaft is supported to revolve in the lower end of short projectors fastened in the cap beam and extending downwards for that purpose. For machines constructed to cut only four feet laths, the driving shaft is about six feet in length, if made of cast iron, the turned bearings are about three inches in diameter, revolving in strong boxes secured to the upper ends of the upright posts. A pair of balance wheels, about five or six feet in diameter and weighing about four hundred pounds each, or sufficient to give the required momentum, when making about fifty revolution a minute, are fastened on the ends of the driving shaft, to revolve either inside or outside of the supporting frame. Or the balance wheel of sufficient weight is fastened on one end of the driving shaft and the driving pulley by the side of a loose pulley on the opposite end of sufficient for short machines.

The fixed cutter of the shear, is an iron or cast a hardened steel bar equal in length to the board the machine is calculated to cut, which may consist of three parts when room for the gauge carriage is required to advance between them. The upper inside corner of this fixed cutter is an angle enough nearly the post and is bolted and fastened along upon the upper side corner of the fixed cutter beam. When the board is advanced by hand, the fixed cutter

may consist of an entire bar, projecting beyond the cutter beam sufficient for the laths to fall upon. The vibrating cutter constituting the other part of the horizontal shear, may also consist of plates, or be made the whole length of the board it is calculated to cut, it is about four or five inches in width, and about three eighths of an inch thick at the back, is only sufficient to ensure the pressure required for cutting the boards, slabs, or planks. The back of this cutter is supported against the shoulder of a square rabbit, made within the front lower corner of the vibrating cutter beam to the front edge of which it is nicely bolted edge downward, and securely fastened by a sufficiency of iron screw bolts with a square countersunk head, and beaded on the side opposite to the fixed cutter.

The vibrating cutter beam is a hard substantial stick of timber, four feet or more in length, and breadth sufficient to prevent it from springing; whose size depends upon the length of boards the machine is calculated to cut. On the vibrating cutter beam in short machine may consist of a broad cast iron plate with a horizontal flange sufficiently broad to prevent the cutter from springing sideways. For cutting four foot laths, the vibrating cutter beam is about four and a half feet in length, including at each end a strong nail or moving joint by which the lower ends of a pair of strong upright pitmans are connected to vibrate by means of iron straps and gibbs, and keys, whose upper ends of these short pitmans are connected in a similar manner, to vibrate upon a pair of cone or cones, from one or two to six or seven inches long according to the length of board it is calculated to cut, and the degree the vibrating cutter is inclined, or adjusted, more or less shearing in relation to the horizontal fixed cutter, which is required to be about three eighths of an inch to a foot of the length of the cutter according to the hardness and thickness of the boards, plank or slabs it is required to cut. For guiding the vibrating cutter beam are eight metal bars, so that the edges of the two end ones will

usually coincide, an upper and lower pair of upright cast iron jaws, are firmly bolted and adjusted on each end of the vibrating cutter beam. On of these cutter beam is made of cast iron, one of each pair is cast mounted on each corner of it, in the same vertical casting, and the other upright jaws are bolted and adjusted by screws to them. These jaws in the operation of the machine slide up and down in upright cast iron guides about an inch and a half square in d. may be of a V form about ten feet in length, with a stiff flange on base on each edge side imbedded and bolted on the inside of each upright post of the supporting frame. In long machines, with but one pair of jaws, and plowing, and the vibrating cutter beam consisting of timber, it may be supported from springing by a vertical frame above and horizontally upon the side in a bracing manner, similar in construction to the principle of an arch. For cutting staves for dry casks or barrels or other strips, that being a little ^{beam} will be no objection to their use, a pair of horizontal bars, with broad heads, are connected to the ends of the vibrating cutter beam by sufficient fastenings, while the opposite ends of these bars, turn upon a pair of joints, or guides, projecting from the inside of that end of the dill, or brace, which are opposite to the end of the frame containing the posts.

For cutting thin strips for bed mats, basketry, chair bottoms, &c. the board is advanced about an eighth of an inch, more or less, at a time, as required for that purpose by means of a gauge carriage, which consists of a pair of horizontal vices made to grip and hold fast the edge of the board in two places, and to advance the same horizontally between the cutters. This carriage consists of a pair of under jaws of the vice, framed parallel to each other upon the ends of a sufficient girder parallel to the fixed cutter beam. These jaws are fixed to their back . . . and pivoted upon a pair of horizontal guiding supports, and within a pair of guides, cut out of the upper surface of the fixed cutter beam to receive it.

to allow them to advance with the board to the cutting edge for cutting it upon the fixed cutter, which consists of three parts terminating on the back side of the under jaws of the ricer for that purpose. The upper jaws of the ricer being the same length, may be made fast with springs to open them at the back ends, with upright screws, near their front ends, which are to turn and hold the board. Or these upper jaws may be made to turn upon a pair of joints, near their front ends, which joints consists of a pair of upright flat studs, formed in mortises, made in the under jaws, with their upper ends, extending loosely in mortises, made in the upper jaws directly above, through each of which studs, and upper mortises, a round half-finished iron pin is, fitted upon which the upper jaws turn. Their back ends having sufficient leverage are pressed apart by a pair of upright screws, or by a pair of button catches or wedges forced by hand for holding fast the board between iron teethed jaws.

This gauge carriage is advanced with the board or plank, the distance the thickness of the stripe are required to be cut by means of a pair of straight racks, fastened to the underside of the under jaws, matching in the teeth of a pair of pinion wheels, fixed upon a horizontal feeding shaft, which is forced to move slowly round beneath, by means of vibrating hands, connecting the motion of the vibrating cutter with a ratchet wheel fixed upon the feeding shaft.

The gauge carriage is advanced with the board at the back of the vibrating cutter, just the thickness of the lath or stripe it is required to cut when forced down for that purpose, by means of the moving hands connected with the motion of the vibrating cutter beam or cam, or crank of the driving shaft, and catching them in the teeth of the ratchet wheel. To effect the alternate vibration of the gauge carriage a small round hole is made through the hub of the ratchet wheel, which has a small grooved wheel with a pair of anti-projecting cutters, formed on one side of it. This gauge wheel is hung between the forks of a forked lever by

which the ratcheted wheel and side catches are forced by the tender to slide about one inch back and forward along the feeding shaft. When the board is made fast in the vices, in readiness to be cut into strips, the tender forces by the purchase of the forked lever the side catches of the grooved wheel to catch another pair of side propelling catch es, made fast to the feeding shaft which thereby advances the gauge carriage until the board is entirely cut into strips, and till when a remover fixed upon the advancing gauge carriage arrives for the purpose of unshipping the weighty extremity of the forked lever. The gauge carriage is thereby forced to recede in readiness for another board, by descent of a sufficient weight suspended to raise by a ^{small} round a broad grooved pulley, fixed upon the feeding shaft, as the carriage advances in cutting the next board by means of the side catches forced again to catch as before, and so on alternately it is impelled to vibrate at the pleasure of the tender. This machine is forced into operation by a moving band connecting the motion of the driving pulley (fastened upon the driving shaft) with that of any sufficient power drum while the previously prepared board, plank, or slate not exceeding the length of the cutter is advanced by hand between them against an adjusted gauge, or by the gauge carriage, while the vibrating cutter cuts the narrow flooring upon a level substrainer till crowded across it by the next. Or of laths or other narrow strips are cut they fall directly into a measure, or upon a moving canvas, or ropes impelled round a pair of round shafts forced by their connection by means of bands, and pulleys with the driving shaft conveying them to fall into a more convenient measure. Or provided the laths or strips be required to be conveyed in uniform parcels, they are effected by means of a moving band connecting the motion of the ground sliding wheel with the motion of a pulley reduced to the required slow motion by pulley gearing or worm and toothed wheel, similar to clock and work

with a projectile acting upon an alarm spring to repeat by a Hooke for every hundred more or less as required, to remind the tender to remove them for use. Having explained the manner of constructing the several parts of this new and useful combination of machinery, and shears with a vibrating cutter, calculated to vibrate in a rectile manner, and have also explained their application, and mode of operation, in cutting the boards, plank or slate, into plastering, laths, narrow flooring, thin splits, and other strips, for various uses, in a new and useful manner, but I have calculated that circumstances may occur in applying to use the principle of my invention, wherein the position of the main driving shaft, in relation to that of the vibrating cutter of the horizontal shears may be required to be placed with equal usefulness to revolve by means of a single as well as a pair of ranks, adjusted to revolve above, back, or below the cutter, and force the vibrating cutter to vibrate horizontally as well as vertically (with or without a joint like common shears, at one end,) and thereby are to require the supporting frame to be shaped, to support the operation of the principle of my invention accordingly. It may be fitted up for operation in a saw mill already built, and be impelled by water and water wheel, or by steam or other power, and the parts, or whole machine may consist partly or wholly of iron or wood as far as practicable, and that the parts be made larger or smaller and the proportion varied from those of the foregoing description, in order for cutting the boards, plank or slate, of various lengths. For further understanding of my invention of this new application, the following drawings, and references to the several parts of the machinery as the same are set forth in this specification will sufficiently show, and enable others skilled in the art of machine building to construct the machinery and put the same into useful operation.

A. A. Main sills. B. B. upright posts. C. one of the braces.

C. fixed cutter beam. Vibrating cutter beam, of driving shaft, one of the pitmans. H. the balance wheel, at the vibration cutter. K. loose pulley. L. Driving Pulley, round which the moving band drives the machine into operation.

As my right to the invention of this new and useful band sawing machine, I claim the application of the combination of the machinery, and shears, with the vibrating cutter, to a new and useful purpose of cutting boards, plank, or stalks, lengthwise into plastered bats, narrow flooring and weaving strips, or splines, as herein before specified, as represented in the accompanying drawings and as applied by me, in a manner never before in useful operation, and claiming only what I have invented, new and useful for myself, my heirs, administrators & executors, the full and exclusive right and liberty of making, constructing and using and vending to others to be used, my said new and useful improvement, within the United States, according to the law for that purpose made and provided.

In testimony that the foregoing is a true specification and description of my lawful claim of said new and useful improvement, I have hereunto subscribed my name, as the inventor of the same, the fourteenth day of September in the year, & thousand Eight Hundred and Thirty one.
